UNITED STATES PATENT OFFICE

MALCOLM B. CUMMINGS, OF TUCSON, ARIZONA

DESIGN FOR A CHAIR

Application filed May 12, 1930. Serial No. 35,595. Term of patent 3½ years.

To all whom it may concern:

Be it known that I, MALCOLM B. CUMMINGS, a citizen of the United States, residing at Tucson, in the county of Pima and State of Arizona, have invented a new, original, and ornamental Design for Chair, of which the following is a specification, reference being had to the accompanying drawing, forming part thereof.

Fig. 2 is a front elevation thereof.

I claim:

The ornamental design for a chair as shown.

MALCOLM B. CUMMINGS.
